UNITED STATES PATENT OFFICE

SIDNEY M. DICKSON, OF PITTSBURGH, PENNSYLVANIA

VENTILATOR

Application filed May 1, 1930. Serial No. 448,828.

This invention relates to building ventilators and more in particular to ventilators with louvers.

One of the primary objects of this invention is to provide a ventilator having adjustable louvers which may be opened more or less to suit, and which will maintain their position under normal operating conditions. Another object is to provide a ventilator having louvers which will automatically close in case of fire causing an undue increase of temperature within the structure in which applied, thus preventing any fire promoting air drafts. A further object is to provide a self-contained louvered ventilator which may be built directly into a wall, without requiring additional lintels and sill members. Yet another object is to provide in such a ventilator simple and durable means for hingedly mounting the louvers without using exposed bolts, screws or the like holding means.

Additional features and advantages of this invention will appear in the following description considered in connection with the accompanying drawings forming a part of this application, and in which:

Fig. 1 is an isometric view of the louvered ventilator, as seen from the outside.

Fig. 2 is a sectional view taken in a plane along line 2—3 in Fig. 1, showing all louvers in "open" position.

Fig. 3 is a similar view, but with the louvers in "closed" position.

Fig. 4 represents a section taken in a plane along line 4—4 in Fig. 1.

Fig. 5 shows a section taken longitudinally in a plane along line 5—5, also in Fig. 1.

Fig. 6 is an inside elevation of one of the louver-leaves provided with a mechanism for holding the louvers in the adjusted "open" position, and for automatically closing the ventilator in case of fire.

Fig. 7 is a section taken along line 7—7, Fig. 1, showing the preferred construction of the jambs of the ventilator.

Fig. 8 is an end view of one of the louver-leaves.

Fig. 9 is an end view of one type of journal bushing used in the ventilator.

Fig. 10 is a side elevation of Fig. 9.

Figs. 11 and 12 show respectively a plan view and a side elevation of a fusible link used in connection with the ventilator.

Fig. 13 is a perspective view of another type of journal bushing, also used in the ventilator.

Reference being had to the drawings, a ventilator built according to this invention consists of a frame-structure comprising the two jambs 1, for channel-shaped cross-section, the lintel 2 and the sill 3 made of any desired sheet metal and preferably built as a unit by welding these parts together, prior to installing the louvers.

The jambs are provided outwardly with close fitting channel-shaped covers 4, thus producing hollow, rectangular shaped, members in which some of the mechanism is fully or partly enclosed. These covers serve also the purpose of preventing the supporting shafts of the louvers from shifting out of place.

The lintel is also of channel-shaped cross-section, open at the top and having inwardly directed stiffening ribs 5. Its strength is sufficient to support the weight of the wall bearing upon it, without requiring special lintels in the construction of the wall.

The sill 3 consists of the outer and inner side walls 6 and 7 having at their lower ends the inwardly turned ribs 8. The top of the sill comprises two stepped off portions 9, 10 connected together by a substantially vertical riser 11. The lower portion 9 slopes towards the outside to drain off any rain water which may fall on it, and the riser forms a stop for the entrance of said water into the building, when the louvers are partly or fully closed.

The number of louver-leaves used in the ventilator depends, of course, on the size of the latter. In the drawings but three leaves are shown. The two lower leaves 12 and 13 are identical, while the upper leaf 14 is slightly modified in that it is provided throughout its length with an angularly disposed blade 15, the purpose of which is to form a seal against air-drafts and rain, when the ventilator is closed, as shown in Fig. 3.

One of the special features of this invention

tion resides in the manner of mounting the louvers without the use of exposed screws, rivets or the like.

As shown, each louver-leaf comprises a main portion 16 terminating at its lower end with an angularly disposed sealing edge 17 and having at the top a channel-shaped head 18 removably fitting about a rectangular supporting rod, or shaft, 19, which latter is made of sufficiently large cross-section to prevent sagging of the louver-leaves in case of intense heat. As will be understood, different cross-sections for the shafts and louver-heads may be used, the main object of using angular cross-sections being to effect the rotation of the louver-leaves with their shafts without having to rely on frictional engagement or on the use of holding bolts, rivets, pins, and so forth.

Each shaft is rockably mounted in one of the jambs by means of a plain bushing 20; and in the other jamb by means of the lever-bushing 21 having a lever or arm 22, the purpose of which is described herebelow. Aside from this structural difference, both types of bushings are alike, and each comprises a cylindrical journal portion 23 and an integral inner flange 24, both having a central aperture 25 of suitable shape and size to receive one end of its corresponding shaft 19. Disposed parallel to one of the sides of the aperture and at a distance thereof slightly greater than the thickness of the louver-leaf, is an inwardly directed lug 26 the purpose of which is to hold the louver-leaf in place on its shaft, after the parts are properly assembled. The journals 23 are freely mounted for rotation in circular apertures, or bearings, 27 cut in the jambs, as suggested in Fig. 10. The purpose of the flanges 24 is to form end-stops for the louver-leaves and keep the latter from rubbing against the inner walls of the jambs.

The various louver-leaves are arranged for simultaneous and equal operation by securing at one end of a louver-shaft an operating lever 28 and by connecting all the parallelly disposed arms 22 of the lever-bushings 21 to a common connecting-rod 29, by means of any suitable hinge-connection, such as, for instance, the bolt-connection 30.

As shown in Fig. 5, in particular, these journals, arms and the connecting-rod are enclosed for the greater part within the hollow jambs, thus affording greater protection against corrosion and dirt, and also facilitating the erection of the assembled ventilator within a wall.

The operating lever 28 may be operated, according to the location of the ventilator, in any desired and suitable manner. In the illustrated embodiment, there is used an endless chain 31 running over a pulley 32 mounted on a jamb of the frame or on a wall. By properly manipulating this chain, the louvers may be adjusted in any desired position.

The louvers are held in the selected position against accidental closing by way of a simple friction device mounted directly on the inside face of one of the louver-leaves. As shown in Fig. 6, friction shoes 33 are rockably mounted on pivots 34 secured adjacent each end of, and to, the louver-leaf. These shoes are brought to exert a suitable pressure against the inner walls of the jambs 1 by means of a spring 35 which is connected to the shoes by means of the hinged links 36, and the tie-rods 37, 38 and 39.

Between the last two rods there is inserted a fusible link 40, of any desired commercial type, the purpose of which is to relieve the brake-shoes of the tension of the spring 35, when a predetermined, dangerous, temperature is reached. The fusible link shown in the drawings comprises two similar flat plates 41, each having at one end an aperture 42 engaged by a tie-rod. These plates are held face to face by means of a solder having a predetermined melting point. When the temperature near the ventilator increases beyond said melting point, the solder will melt and the plates 41 will separate, thus freeing the brake-shoes of the spring tension and allowing the louver-leaves to drop into closed position, due to their own weight, as well as that of the levers 22 and their connecting-rod 29, etc. If desired, a turn-buckle 43 may be used in one of the tie-rods to regulate the tension in the spring 35, and consequently the pressure of the brake-shoes on the jambs.

It will be observed from the drawings that when the louvers are closed, their sealing edges 17 will contact with the heads 18 of the next lower louver and with the riser 11 of the sill, while the extension 15 on the upper louver will seal the space at the top of the ventilator.

Also, any excessive increase of the air pressure within the building, such as due to explosions, will overcome the weight of the louvers and the friction of the various moving parts of the ventilator, and temporarily open the louvers, which will then act as a safety valve, thus preventing any serious damage to the building structure and the machinery or other property stored therein.

While I have illustrated and described herein the preferred embodiment of my invention, and one which I have found by actual test to be very practical, it may be thought desirable, after continued experience, to make slight changes in the construction and arrangement of the details of my invention, and I intend to include all such variations as fall within the scope of the appended claims.

I claim:

1. In a ventilator, a frame structure; a plurality of louvers; a polygonal supporting shaft for each louver; a polygonal head on each louver, said head engaging only a part

of the contour of said shaft and being removable therefrom in a transverse direction; journal means for rotatably mounting the shafts in said frame structure, and means to simultaneously rotate said louvers.

2. In a ventilator, a frame structure; a plurality of louvers; a polygonal supporting shaft for each louver; a polygonal head on each louver, said head engaging only a part of the contour of said shaft and being removable therefrom in a transverse direction; journal means for rotatably mounting the shafts in said frame structure; means positioned on the journals to hold the louvers on their respective shafts, and unitary means to simultaneously rotate said louvers.

3. In a ventilator, a frame structure; a plurality of louvers; a quadrilateral supporting shaft for each louver; a head on each louver longitudinally open at one side and engaging three consecutive sides of said shaft and removable therefrom in a transverse direction; journal means for rotatably mounting the shafts in said frame structure; means positioned on said journals to hold said louvers on their respective shafts; unitary means to simultaneously rotate said louvers; spring actuated means positioned on one of the louvers to hold same in selected open position, and heat controlled fusible means in cooperative relation with said holding means to effect the closure of said louvers by gravity.

4. In a ventilator, a frame structure; a plurality of louvers rockably mounted in said frame structure; unitary means to simultaneously operate said louvers, and frame engaging means positioned on one of the louvers to frictionally hold same in selected open position, said holding means comprising friction shoes hingedly mounted on said louver and connecting means normally under tension to hold said shoes in contact relation with said frame structure.

45 5. In a ventilator, a frame structure; a plurality of louvers rockably mounted in said frame structure; unitary means to simultaneously operate said louvers, and frame engaging means positioned on one of the louvers to frictionally hold same in selected open position; said holding means comprising friction-shoes hingedly mounted on said louver and connecting means normally under tension to hold said louvers in contact relation with said frame structure, and heat controlled fusible means in cooperative relation with said connecting means and adapted to break the contact relation between the friction-shoes and frame structure when subject to a predetermined temperature.

In testimony whereof I affix my signature.
SIDNEY M. DICKSON.
